[57] CLAIM

The ornamental design for a wooden roofing tile, as shown.

DESCRIPTION

FIG. 1 is a side elevational view of a wooden roofing tile showing my new design;
FIG. 2 is a top plan view thereof;
FIG. 3 is a cross-sectional view thereof taken along line 3—3 in FIG. 1;
FIG. 4 is a bottom plan view thereof; and
FIG. 5 is a perspective view thereof on a reduced scale.

FIG. 5

FIG. 4
